REFRIGERATING APPARATUS

Wilford H. Teeter, Dayton, Ohio, assignor to
General Motors Corporation, Dayton, Ohio, a
corporation of Delaware

Application July 19, 1934, Serial No. 736,031

4 Claims. (CL 230—229)

This invention relates to refrigerating apparatus and more particularly to a valve for compressors for refrigerating apparatus.

It is an object of the invention to provide a valve for passing refrigerant therethrough in one direction only, which is not only reliable, quick and positive in its action, but which is also free from the production of noise in its operation.

10 It is also an object to provide a valve for passing of refrigerant in one direction only, which comprises really a pair of valves, one of which opens to a small degree very slightly before the other one opens, to avoid a sudden change in pressure between one side of the valve and the other and to thus eliminate noise in opening and closing.

Further objects and advantages of the present invention will be apparent from the following description, reference being had to the accompanying drawing, wherein a preferred form of the present invention is clearly shown.

In the drawing:

Fig. 1 is a diagrammatic view of a refrigerating system embodying the present invention;

Fig. 2 is a vertical cross section of a compressor piston embodying the present invention and showing the valve in closed position;

Fig. 3 is a view corresponding to Fig. 2 showing the valve in partly open position;

Fig. 4 is a top view of a compressor piston embodying the present invention; while

Fig. 5 is a view corresponding to Fig. 4 with certain of the parts removed to illustrate the piston construction thereunder.

Referring now to Fig. 1, there is shown a refrigerating system comprising a compressor 10 having a piston 12 adapted to be reciprocated in the usual manner in a cylinder 14. A discharge valve 16 is located above the cylinder 14 and communicates by a discharge conduit 18 with a condenser 20. The condenser 20 is connected to a liquid refrigerant receiver 22 which is in communication, by means of a conduit 24, with the evaporator 26 which may contain the usual float valve (not shown) for regulating the expansion of refrigerant therein. A suction conduit 28 communicates between the evaporator 26 and the crank case 29 of the compressor 10, and has a branch 30 containing a bellows 32 forming part of a low pressure control switch 34 for controlling a motor 36 which is adapted to drive the compressor 10 by suitable driving connections (not shown).

The piston 12 contains an inlet valve mecha-

nism for passing gaseous refrigerant from the crank case to the compression cylinder. The inlet valve comprises an annular valve seat 38 within which is provided a series of passages 40 communicating with the under side of the piston head. An auxiliary seat 42 is provided on the piston head concentric to the valve seat 38 and inside the innermost portion of the passages 40. The face of the seat 42 is very slightly lower than the face of the seat 38. This feature 10 appears exaggerated in Figs. 2 and 3 in order to more clearly illustrate the invention. In practice, however on a valve of the order of an inch in diameter, the seat 42 may be approximately .004 or .005 of an inch below the seat 38 15 for best results. A valve disc 44 of a thin resilient flexible material, such as spring steel, is adapted to rest on top of the seat 38 and is biased to close the valve by a leaf spring 46. A cover plate 48 is secured to the piston head by 20 bolts 50 and provides a valve chamber 52 which is in communication with the compression cylinder by a series of ports 54. A central aperture 56 is located in the cover plate immediately 25 above a corresponding central aperture 58 in the valve disc 44.

In operation, gaseous refrigerant is withdrawn by the compressor from the evaporator 26 through the conduit 28. From the crank case, gaseous refrigerant passes through the piston valve into the cylinder 14 from whence it is compressed and ejected through the exhaust valve 16 and conveyed by the conduit 18 to the condenser 20. The refrigerant liquefied in the condenser 20 is collected in the receiver 22 from whence it is conveyed by the conduit 24 to the evaporator 26, where the float valve (not shown) admits liquid refrigerant in amounts varying with the rate of vaporization therein. The switch 34 controls operation of the motor 36 in accordance with the pressure conditions existing in the conduit 28 and evaporator 26.

The operation of the valve shown in Figs. 2 to 5 is such that on the compression or upward stroke of the piston, the parts lie in the position shown in Fig. 2, wherein the valve disc 44 is flexed by the pressure of the gas in the cylinder to close both the seat 38 and the seat 42, thus preventing any passage of refrigerant from the cylinder back to the crank case. After the compression stroke is ended, and the piston begins its down stroke, the pressure difference between the two sides of the piston head is reduced to a point where the resilience of the disc 44 is sufficient to permit the same to straighten out and rise 35

from the seat 42 as shown in Fig. 3. This provides a very small leakage path across the seat 42 and through the aperture 58. As soon as the pressure in the cylinder is sufficiently lower than that of the crank case to overcome the spring 46, the entire valve disc 44 is raised from the seat 38 permitting free passage of gas from the crank case to the cylinder 14. At the bottom of the stroke, the pressure of the cylinder and the crank case are again equalized and the valve disc 44 returns to the seat 38 while the leakage path across the seat 42 is still maintained open. After the piston again begins its compression stroke, the cylinder pressure increases above the crank case pressure to a point sufficient to flex the disc 44 into the position shown in Fig. 2 wherein the leakage path across the seat 42 is again closed.

It will be seen that the provision of a small leakage immediately before opening of the main valve and immediately after closing thereof, tends to cushion both the opening and closing movements of the valve in that it prevents any sudden pressure changes between the two sides of the valve such as occur in ordinary valves of this general type without the additional valve seat 42.

It will be understood that while the invention has been illustrated as applied to a piston valve, its advantages are likewise useful in other applications such as for discharge valves for compressors and, in fact, in any situation requiring a light, quick acting, one way valve which is not only positive and reliable in its action, but which must also be free from any noise in rapid operation.

While the form of embodiment of the invention as herein disclosed, constitutes a preferred form, it is to be understood that other forms might be adopted, all coming within the scope 40 of the claims which follow.

What is claimed is as follows:

1. A fluid control means operated by pressure differences thereon including means forming a throttling passage and a second passage, valve 45 means for controlling the flow of fluid through said passages, said valve means being inherently biased to open the throttling passage and to close the second passage when no pressure differential exists, said valve means being moved by one pres-

sure differential to close both passages and being moved by an opposite pressure differential to open both passages, said throttling passage being always open when said second passage is open and being also opened to permit partial equalization of pressures immediately preceding the opening of the second passage. 5

2. A fluid control means operated by pressure differences thereon including means forming a throttling passage and a second passage, valve 10 means for controlling the flow of fluid through said passages, said valve means being inherently biased to open the throttling passage and to close the second passage when no pressure differential exists, said valve means being moved by one pressure differential to close both passages and being moved by an opposite pressure differential to open both passages, said throttling passage having a cross-sectional area less than one sixteenth the area of the maximum valve opening. 20

3. A compressor comprising a cylinder, a piston therein having a fluid control means comprising a plurality of valve seats located one within the other, one of said valve seats being slightly out of the plane of the other valve seat, a substantially flat resilient disc valve adapted to make sealing engagement first with one of the valve seats and then with another, said valve being provided with a throttling passage opening into the confines of one of said valve seats, said throttling passage having a cross-sectional area less than one sixteenth the area enclosed by one of the seats. 25

4. A fluid control means comprising a plurality of valve seats located one within another, one of said valve seats being slightly out of the plane of the other valve seats, a flat resilient disc valve adapted to make sealing engagement first with one of the valve seats and then with another, one of the valve seats enclosing an area 40 more than four times the area enclosed by the second valve seat, said disc valve being provided with a throttling orifice therein opening into the confines of one of said valve seats, said throttling orifice having an area less than one-fourth the 45 area enclosed by the smaller valve seat, said disc valve being wholly free of any connection with either of the valve seats. 35
